UNITED STATES PATENT OFFICE.

STEPHEN D. BAKER, OF NEW HAVEN, CONNECTICUT, ASSIGNOR TO THE PECK BROS. & CO., OF SAME PLACE.

DESIGN FOR A SIPHON-JET SLOP-SINK.

SPECIFICATION forming part of Design No. 34,143, dated February 26, 1901.

Application filed February 4, 1901. Serial No. 46,031. Term of patent 14 years.

To all whom it may concern:

Be it known that I, STEPHEN D. BAKER, of New Haven, in the county of New Haven and State of Connecticut, have invented and produced a new Design for a Siphon-Jet Slop-Sink; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of a siphon-jet slop-sink embodying my design; Fig. 2, a plan view thereof; Fig. 3, a front view.

This invention relates to a design for a siphon-jet slop-sink; and the design consists in the configuration of the sink, as herein-after described, and shown in the accompanying illustrations.

As herein shown, the design consists in a basin A, which may be described as being substantially square in general form, because that is the impression it makes upon the eye when looked down upon or seen in plan and because its horizontal sections would present a square figure with rounded corners, though the exterior of the basin if seen from below presents convex surfaces. The upper edge

of the basin is formed with a roll B, from which the lines of the basin converge inwardly on flowing lines to a narrow pedestal C, the axis of which runs parallel with a line drawn from the center of the front of the basin through the projection D, formed at the rear thereof. In other words, the said foot runs from front to back. Its ends are rounded and its sides substantially flat in general aspect. Upon its lower end the pedestal is formed with and encircled by a horizontal flange-like foot E. A long mound-like protuberance F extends from the base of the basin downward and forward over one side of the pedestal. The lines of the basin and pedestal merge into each other for the most part in graceful curves, all as shown in the accompanying illustrations.

I claim—

The design for a siphon-jet slop-sink, as herein shown and described.

In testimony whereof I have signed this specification in the presence of two subscribing witnesses.

STEPHEN D. BAKER.
